UNITED STATES PATENT OFFICE.

SAMUEL F. CLOUSER, OF NEW YORK, N. Y.

DESIGN FOR A WASHER.

SPECIFICATION forming part of Design No. 29,541, dated October 25, 1898.

Application filed September 17, 1898. Serial No. 691,247. Term of patent 7 years.

To all whom it may concern:

Be it known that I, SAMUEL F. CLOUSER, a citizen of the United States, residing in the city of New York, borough of Brooklyn, county of Kings, and State of New York, have invented and produced a new and original Design for Washers, of which the following is a specification, reference being had to the accompanying drawings, forming part thereof.

10 In the drawings forming part of this specification, Figure 1 is a plan view of my washer, and Fig. 2 a side view thereof, these two views being deemed necessary to fully illustrate my design.

15 As shown in the drawings, my newly-designed washer consists of a spiral coil A, the upper convolutions or circles of said coil gradually decreasing in size and one end of the coil terminating at one side of and within the 20 upper convolution or circle of said coil, as shown at B, and the other end terminating in

the same plane as the bottom convolution or circle of said coil and provided with an outwardly-directed projection C, and as thus formed the outer diameter of each successive 25 circle or convolution of the spiral coil above the first convolution or circle is less than the inner diameter of the convolution or circle of the coil immediately below it.

Having fully described my invention, I 30 claim as new and desire to secure by Letters Patent—

The design for a washer herein shown and described.

In testimony that I claim the foregoing as 35 my invention I have signed my name, in presence of the subscribing witnesses, this 16th day of September, 1898.

SAMUEL F. CLOUSER.
